UNITED STATES PATENT OFFICE

GEORGE WARREN HIRSHSON, OF NEW BEDFORD, MASSACHUSETTS, ASSIGNOR TO
GEORGE H. REYNOLDS, OF NEW BEDFORD, MASSACHUSETTS

ADVERTISING DEVICE FOR LETTERHEADS, FOLDERS, AND THE LIKE

Application filed December 18, 1930. Serial No. 503,279.

This invention relates to an advertising device for letterheads, folders and the like, which I prefer to term an "outstand-ad". Its object is to provide a device in which a small card or tab is movably attached to a main sheet such as a letterhead, folder or the like and which is connected thereto in such a manner as to stand out from the body of the sheet and shake or move about when the letterhead or folder is handled, thereby attracting attention to the advertisement, picture or other matter that may be printed on the front surface of the tab.

The invention is illustrated in the accompanying drawings, in which:

Figure 1 is a front view of a letterhead with the invention applied thereto;

Figure 2 is a section on the line 2-2 of Figure 1 showing the tab pressed back toward the sheet;

Figure 3 is a side view showing the tab standing out from the sheet;

Figures 4, 5 and 6 illustrate different forms of cuts which may be made in the sheet to provide the arms to which the tab is secured; and

Figures 7 and 8 show other methods by which the tab may be secured to the main sheet.

Referring to the drawings in detail, the numeral 10 indicates a main sheet such as the letterhead, folder or other sheet and 11 the card or tab secured thereto. To attach the tab to the sheet, various methods may be used. According to one method, I cut out a portion of the sheet 10 to form arms 12 which are bent outwardly in front of the sheet 10 and the outer ends 13 thereof are pasted or otherwise secured to the rear sur-

face of the tab 11. The arms 12 may be formed by cutting out the sheet 10 in different ways as illustrated in Figures 4, 5 and 6. The arms 12 serve to hold the tab in front of the sheet and cause it to stand out from the front surface thereof. These arms are cut of such size as to be flexible and yieldable so that the tab is more or less loosely connected to the sheet, with the result that as the sheet is handled or moved about the tab

attention. The arms 12 are sufficiently flexible as to permit the tab to be pressed back against the front face of the sheet so that it will not interfere when the sheet is passed into a typewriter or folded flat as for insertion in an envelope. The tab is preferably made of sufficient size to cover and thereby conceal the arms 12 and the cut-out portion of the sheet from which the arms are formed.

Instead of cutting out the main sheet, the flexible arms may be formed as an integral part of the tab and bent rearwardly thereof and secured to the main sheet. Such an arrangement is illustrated in Figure 7 in which the arms 12a are integral with the tab 11a, the arms being bent rearwardly and having their rear ends 14 pasted or otherwise secured to the main sheet.

In some cases it may be preferable to form the arms from a narrow strip of paper or other suitable material separate and distinct from the main sheet or the tab. Such an arrangement is shown in Figure 8 in which the flexible arms 12b are formed of a separate strip of material having the intermediate portion 15 thereof secured to either the sheet 10 or the tab 11b and the end portions 16 thereof secured to the other part. This arrangement produces flexible arms connecting the sheet and tab, as in the other forms described.

The front surface of the tab is adapted to receive printed matter such as an advertisement, picture, trade slogan, etc., and as the tab is more or less loosely connected to the sheet, it will shake or move about when the sheet is picked up or handled thereby attracting attention to the advertisement or other matter thereon.

Having thus described the invention, what is claimed as new and desired to be secured by Letters Patent is:

1. An advertising device comprising, in combination, a main sheet of paper or the like having portions thereof cut out and bent forwardly of the sheet to form flexible arms integral with the sheet, and a flat tab arranged in front of said sheet, said tab being of larger size than said cut-out portion on the main sheet, said arms being secured to

- the rear surface of said tab at spaced points, said arms normally causing said tab to stand out from the main sheet but being sufficiently flexible to bend and permit the tab to move relative to the sheet and to be pressed against the sheet, said arms being foldable into the cut-out portions of the sheet when the tab is pressed toward the sheet, said tab having a flat front surface for receiving printed or other matter.
- 10 2. An advertising device comprising, in combination, a main sheet of paper or the like having portions thereof cut out and bent forwardly of the sheet to form flexible arms integral with the sheet, said arms being arranged to be folded back into the openings from which they are cut, a flat tab arranged in front of said sheet and in front of said cut-out portions and covering the latter, said arms being secured to the rear surface of said tab at spaced points, said arms normally causing said tab to stand out from the main sheet but being sufficiently flexible to bend and permit the tab to move relative to the sheet and to be pressed against the sheet with the arms pressed into said openings, said tab having a flat front surface thereon for receiving printed or other matter.

In testimony whereof I hereunto affix my
30 signature.

GEORGE WARREN HIRSHSON.
